H. G. KUPER.

DEVICE FOR TRUING CRANK SHAFTS OF ENGINES.

APPLICATION FILED JAN. 29, 1919.

1,378,799.

Patented May 17, 1921.

Inventor

H. G. Kuper.

By *John Murphy, Jr.* attorney.

UNITED STATES PATENT OFFICE.

HENRY G. KUPER, OF COLUMBUS, NEBRASKA.

DEVICE FOR TRUING CRANK-SHAFTS OF ENGINES.

1,378,799.

Specification of Letters Patent.

Patented May 17, 1921.

Application filed January 29, 1918. Serial No. 273,773.

To all whom it may concern:

Be it known that I, HENRY G. KUPER, a citizen of the United States, residing at Columbus, in the county of Platte and State

5 of Nebraska, have invented certain new and useful Improvements in Devices for Truing Crank-Shafts of Engines; and I do hereby declare the following to be a full, clear, and exact description of the invention, such 10 as will enable others skilled in the art to which it appertains to make and use the same.

This invention relates to improvements in devices for truing crank shafts of engines 15 and has for one of its objects the provision of a device of this character, wherein the bearing engaging portions of a crank shaft can be trued when worn irregular without removing the crank shaft from the engine. 20 Another object of this invention is the provision of means adapted to form the lower half of a bearing of a connecting rod and is equipped with a cutting or shaving blade that will remove the irregular surface 25 of the bearing engaging portions on rotating the crank shaft manually.

A further object of this invention is the provision of means for adjusting the blade or knife so that its cutting or shaving capacity can be varied thus permitting of the 30 device being used on crank shafts of different diameters and also where the bearing engaging portions vary according to their irregular surfaces.

35 A still further object of this invention is the provision of a device for truing crank shafts of engines of the above stated character, which shall be simple, durable and efficient, and which may be manufactured 40 and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a fragmentary vertical sectional view illustrating my invention applied to the crank shaft and the connecting rod thereof,

Fig. 2 is a perspective view of the device

for truing crank shafts of engines and which is constructed in accordance with my invention, and

Fig. 3 is a transverse sectional view of the same.

Referring in detail to the drawing, the numeral 1 indicates as an entirety an engine including the usual crank case 2, and crank shaft 3 having connected to its crank portion 4 a connecting rod 5. In Fig. 1 I have elected to show my invention applied to one of the connecting rods 5 and in order to apply the same, the crank case 2 is dropped or removed from the base of the engine exposing the crank shaft and its various connecting rods.

In applying my invention to the crank portion which is desired to be trued or removed of its irregular surfaces, the lower half of the bearing of the respective connecting rod is removed and my invention applied to the upper half and about the crank portion of said crank shaft. The body 6 has formed thereon arcuate shaped extensions 7 that receive approximately one-half of the bearing engaging portion of the crank shaft and is provided with oppositely disposed ears 8 to receive the bolts of the connecting rod 5, whereby the body is secured in position. The body 6 is provided with a slot 9 that has its upper edge open through the extension 7 and slidably receives a knife or blade 10. This knife or blade has its upper edge provided with a cutting face 11 adapted to engage the bearing engaging portions of the crank shaft. The blade or knife 10 is held within the slot 9 by means of set screws 12 carried by the body 6. Adjusting screws 13 are mounted in the body and engage the lower edge of the knife for adjusting the same within the slot 9 and also for forcing the cutting edge or face into engagement with the bearing engaging portions of the crank shaft.

With the body 6 applied to the connecting rod 5, and with the knife or blade 10 properly adjusted, the crank shaft is manually rotated and as the same rotates within the body 6 and the upper half of the bearing of the connecting rod the knife or blade removes the irregular surface of the bearing engaging portion of the crank shaft, thus it will be seen that the bearing engaging portions of the crank shaft can be readily trued without removing the crank shaft from the engine.

While I have shown and described the preferred embodiment of my invention, it will be understood that minor changes in construction, combination, and arrangement 5 of parts may be made without departing from the spirit and scope of the invention as claimed.

Having thus described my invention, what I claim is:—

- 10 1. A device for truing crank shafts including a connecting rod and its integral bearing section receiving one-half of the bearing portion of a crank shaft, a body, arcuate-shaped extensions formed on said body and detachably secured to the bearing section, and a knife carried by said body and adapted to shave the face of the bearing portion on rotation of the crank shaft.
- 15 2. A device for truing crank shafts including a connecting rod and its integral bearing section receiving one-half of the bearing portion of a crank shaft, a body of the same length as the integral bearing sec-

tion, arcuate-shaped extensions formed on said body and detachably secured to the 25 bearing section, a longitudinally extending knife carried by said body and adapted to shave the face of the bearing portion on rotation of the crank shaft, and means adjusting the knife in relation to the bearing portion of the crank shaft. 30

3. A device for truing crank shafts including a connecting rod and its integral bearing section receiving one portion of the bearing portion of the crank shaft, a body detachably secured to the bearing section, and a knife carried by said body and adapted to shave the face of the bearing portion on rotation of the crank shaft.

In testimony whereof I affix my signature 40 in presence of two witnesses.

HENRY G. KUPER.
